UNITED STATES PATENT OFFICE.

JESSE W. D. DAVIS, OF LAMPASAS, TEXAS.

BATHING-SUIT.

SPECIFICATION forming part of Letters Patent No. 601,556, dated March 29, 1898.

Application filed February 13, 1897. Serial No. 623,222. (No model.)

To all whom it may concern:

Be it known that I, JESSE W. D. DAVIS, of Lampasas, in the county of Lampasas and State of Texas, have invented a new and useful Improvement in Bathing-Suits, of which the following is a specification.

My invention is an improvement in bathing-suits, and has for an object to provide a simple inexpensive bathing-suit which will 10 effectually prevent exposure of the person, can be easily and quickly dried, will not cling to the bather, and may be easily cleaned.

The invention consists in certain novel constructions, combinations, and arrangements 15 of parts, as will be hereinafter described, and pointed out in the claims.

In the drawings, Figure 1 is a side view of 20 a bathing-suit constructed according to my invention. Fig. 2 is a vertical longitudinal 25 section of the skirt portion. Fig. 3 is a view of the outer or bottom side of the veil. Fig. 4 is a view of the top of said veil. Fig. 5 is a detail view of the detachable border, and Fig. 6 is a detail view of the waistband portion of 30 the skirt.

The suit has a body, basque, or blouse A and a skirt B, buttoned or otherwise suitably connected, and is made of practically waterproof material, preferably cloth, having an 35 outer face of rubber or other waterproof material, either of corrugated or smooth surface, and having openings C, covered by shields D, in the form of caps secured by cement or otherwise above the holes C, extending down 40 over the same and open at the bottom, permitting the free ingress and egress of water from the interior of the suit. Light rubber straps E are cemented to the inside of the suit and operate to hold the corrugations in shape.

In the lower part of the skirt I fit the transverse diaphragm-like piece F, which for convenience of reference I term the "veil," and which, like the rest of the skirt, is preferably 45 of rubber and is detachably secured to the skirt by flexible cords and buttons, as shown. This veil has at its edges short straps, preferably of elastic, buttoned to the skirt at or near the lower edge thereof. This veil F is 50 provided with openings G for the legs, which openings may preferably be arranged slightly in advance of the center. Short trouser por-

tions H in the nature of bloomer-shaped pantalets depend from the veil surrounding the openings G and are provided at their lower 55 ends with buckles h or other suitable fastenings by which they may be fastened a little below the knee of the wearer. At their juncture with the veil these pantalets extend from near the center of the veil nearly to the 60 edge of veil, as best shown in Fig. 5.

Straps I, preferably of elastic material, are secured to the middle of the veil and tend to support the same. These supporting-straps in operation pass up and are attached at each 65 side of the waist. A corrugated rubber ruffle J extends around and is secured to the inner side of the skirt at the bottom thereof. I also provide corrugated ruffles J' on the veil extending around the pantalets close to the 70 edge of the veil. These ruffles and veil operate to give the appearance of a multiplicity of skirts, so that a woman lying on her body in the water will be protected and have the appearance of wearing many underskirts. 75

A border K, made of plain rubber cloth of any width to suit the wearer, may be provided and attached to the bottom of the skirt by buttons or the like, so it can be used or not, as desired, and borders of different widths may 80 be supplied, so persons of different heights may be properly fitted.

In operation the water will pass under the shields D through the openings and will thoroughly wash the body, the veil and ruffles 85 preventing any exposure of the person. The corrugated rubber facing will hold the suit in shape and prevent any clinging to the person. The veil being supported by the straps or cords I does not interfere with the movements of the bather and avoids the dragging 90 of the skirt by the limbs, the suit holding and maintaining its shape while the wearer is moving.

The holes on waist or bust running with the 95 corrugations provide an inlet for water that will not close up from pressure of waves and the bust will have a corset-shape, making a neat-fitting garment. I supply the waist with a flap a (see dotted lines, Fig. 1) to protect the 100 person from exposure if a front button is unfastened.

The garment may be finished and ornamented to conform with any change of fash-

ion and such finish and ornamentation may be carried out in rubber dress material. The suit does not require to be washed or laundered, but may be cleaned by simply rinsing it off when it will dry in a few minutes.

The improvement may be carried out in bathing-suits for men.

The skirt is formed at the top with a front flap L, buttoned at its edges at L', and with an inner belt-strap L². This belt-strap L² is secured at L³ to the skirt and has buttons or other suitable fastenings L⁴ at its free end.

Having thus described my invention, what I claim as new, and desire to secure by Letters Patent, is—

1. A bathing-suit comprising a skirt, a transverse diaphragm in the lower part of said skirt provided with openings for the legs of the wearer, and supporting-straps secured at one end to the middle of the diaphragm where-

by they may operate to draw the diaphragm into conical form, and connected at their upper ends with the waistband of the skirt substantially as shown and described.

2. A bathing-suit comprising a skirt of waterproof material having openings for the ingress of water, the diaphragm in the lower end of said skirt secured thereto at intervals and having openings between it and the skirt for the egress of water, and the straps connecting said diaphragm with the upper portion of the skirt and holding the diaphragm in conical form whereby water may pass freely therefrom to the outlets between it and the skirt substantially as shown and described.

JESSE W. D. DAVIS.
